UNITED STATES PATENT OFFICE.

WILLIAM ROBERT DOUGAN, OF SOMERSET, PENNSYLVANIA.

TOOTHBRAH.

Application filed April 9, 1926. Serial No. 100,934.

This invention relates to an attachment for tooth brushes or the like and aims to provide novel means whereby a person after cleaning his teeth may massage the gums to increase the circulation of blood through the gums to strengthen the teeth and insure a healthy condition of the gums.

An important object of the invention is to provide a device of this character which may be readily slipped over the handle of a tooth brush so that the same may be conveniently operated, the handle of the tooth brush acting as the support for the massaging device.

A still further object of the invention is to provide a device of this character which will operate on both sides of the gums simultaneously.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is an elevational view of one side of a device constructed in accordance with the invention.

Figure 2 is a front elevational view thereof.

Figure 3 is a vertically sectional view through the massaging device.

Figure 4 is an end elevational view thereof.

Referring to the drawing in detail, the reference character 5 indicates a tooth brush handle on which the device forming the subject matter of this invention is more particularly adapted for use, however it is to be understood that the device may be so constructed that it may be positioned over the person's finger, for massaging purposes.

The device includes a body portion 6 formed with an opening for the reception of the handle of the tooth brush as shown by the drawing. Formed integral with the

body portion 5 is an extension 7 which is preferably round in cross section and relatively wide, so that the same will contact with a great portion of the gums of the user.

Associated with the portion 7 is an outwardly extended substantially wide portion 8, the outer end thereof being extended inwardly as at 9 to contact with the gums at the opposite sides of the teeth, the space between the members 7 and 8 being occupied by the teeth of the person using the device, when the device is positioned to accomplish the massaging result.

In order that a certain amount of pressure will be exerted against the gums, the members 7 and 8 are reinforced by a flexible wire 10 which is embedded therein during the construction of the massaging device, and in view of the fact that the device is formed preferably of rubber, the positioning of the member 10 may be accomplished with facility during the construction of the device.

In the use of the device, it is obvious that the device may be positioned within the mouth so that the substantially wide portions thereof will contact with the gums at points adjacent to the bases of the teeth, whereupon a movement directed thereto, similar to the movement of a tooth brush being operated for cleaning the teeth, will increase the circulation of blood through the gums to strengthen the teeth and insure a healthy condition of the gums at all times.

I claim:

A massaging device including a body portion having spaced gum engaging members of loop construction, one of the gum engaging members being curved towards the adjacent gum engaging member, a wire embedded in each gum engaging member, the wires conforming to the shapes of the gum engaging members and extending throughout the entire lengths thereof to normally hold the gum engaging members against distortion, and said body portion having a socket to receive the handle of a tooth brush.

In testimony that I claim the foregoing as my own, I have hereto affixed my signature.

WILLIAM ROBERT DOUGAN.
